BASIL E. BROWN, OF PONTIAC, MICHIGAN

ADJUSTABLE SUPPORT FOR ANGLE BARS

Application filed February 19, 1930. Serial No. 429,535.

This invention relates to the provision of a secure and yet adjustable support in the poured-in concrete structural mass of a building whereby, when the finishing of the exterior of the building calls for the application to the outside surface of the concrete of a layer of brick, terra cotta, or the like, the support for the lower courses thereof may be very accurately positioned by the use of plain angle irons in conjunction with the elements herein to be described. This becomes of special importance where, as is generally the case, as regards the sequence of steps in the completion of an office building, it is intended that the lower two or three stories shall be of highly polished granite, marble or the like, the slabs of which are, for the sake of avoiding injury during the structural operations, put in position only shortly before the building is completed. This involves the starting of the brick work or terra cotta, which is to form the facing of the upper structure, without waiting for the installation of these lower course granite blocks, consequently in order that the fit of these latter may be mathematically exact with reference to the already placed brick facings thereof, great accuracy of adjustment is necessary as to the structural iron or steel parts, such as angle irons, which are generally employed to support the lowermost course of the brick structure meantime.

Previous use of angle irons for this purpose of which I am aware, has involved their support relatively to the building structure by means of bolts or other elements passing through holes which must be very carefully positioned in the vertical web of the angle iron employed, and consequently admit of no upward or downward adjustment except at the price of their removal and the boring of new and correctly positioned holes, or the use of slots through some portion of which a holding bolt may pass.

By the use of my improved organization of parts I am enabled to secure all of the advantages resulting from the use of angle irons for this purpose, while still leaving them adjustable upward or downward to

the degree necessary to allow for the accurate matching of the top edge of the uppermost marble, or granite block exactly beneath the lower-most brick course, none of the angle irons needing to have any such holes bored in their vertical webs. My preferred embodiment of the means for accomplishing this is illustrated in the accompanying drawings, wherein:

Figure 1 is a view of a pair of adjustable angle iron supports positioned in a concrete wall structure and as viewed from the outside thereof.

Figure 2 is a largely sectional elevational view taken along the line 2-2 of Figure 1 and looking in the direction of the arrows there shown.

Figure 3 is a larger scale elevational view looking in the opposite direction from that of Figure 2 and showing the positioning of the shell or box, which is set into the concrete mass, relatively to the temporary wooden holding structure, which confines the concrete when first poured and during its hardening.

Figure 4 is a front elevation of one of my improved devices in general resembling on a larger scale, one of the parts shown in Figure 1.

Figure 5 is a top view of the box structure shown elevationally in Figure 4.

Figure 6 is a large scale view corresponding in the direction from which it is taken to partly sectional Figure 2, but like Figure 3, bringing out the temporary positioning of the wooden concrete forms relatively to the permanent structure, being taken along the line 6-6 of Figure 4 and looking in the direction of the arrows there shown.

Figures 7 and 8 are partly sectional plan views of slightly variant but similarly functioning forms of my improved organization of parts, taken along the line 8-8 of Figure 4 and looking in the direction of the arrows there shown.

Figure 9 is a front elevational view of the hanger which forms one of the co-operative parts of my adjustable construction.

Figure 10 is a plan view from above of the hanger shown in Figure 9.

Figure 11 is a front elevational view of the supporting clip which forms another of the cooperative parts.

Figure 12 is a plan view from above of 5 the clip shown in Figure 11.

A indicates a cement or other permanent structural part of a building wall, into which there are sunk, at desired intervals and embeddingly surrounded by the poured- 10 in cement, boxes or shell pieces B, preferably provided with vertically extending bottom portions C and with flanges D, which, when the cement has hardened, are designed to lie substantially coincidentally with the 15 plane of the outer surface thereof. If desired, the box may be provided with flanges or projections B' which serve to additionally effect the anchorage of the box in the concrete mass. In Figures 3 and 6 I have 20 shown temporary wooden forms F for the confinement of the cement while plastic within desired limits, to the inner faces of which the flanges D of the box A are secured as by means of holding nails or bolts G when 25 the wooden forms are erected and before the pouring in of the cement is begun. Positioned within the space E, formed by the box, is a threaded bolt H which passes through 30 suitably positioned and threaded apertures in the top holding clip J and the hanger K, the former of which it will be noted is of cross-sectionally L-shaped, while the latter which, as brought out particularly in Figure 35 6, is of a straightened-out Z-shaped form in that its top web or flange K', through which the bolt H engages, and its lower web K², extend from opposite edges of the central portion K and in opposite directions.

The outer or shorter depending end J' of 40 the clip J is provided with a threaded hole through which the adjusting nut L extends for the engagement of its inner end against the vertically positioned portion M of the angle iron whose elbow and whose horizontal section N, rest upon the flange K² of the hanger K. Upon this horizontal flange or web N are desired to rest the brick courses 45 Q, with which the building is to be faced.

The cement having hardened and the box 50 B being accurately held fixedly in position therewithin, careful measurement relatively to the ground line of the building under construction is indulged in to determine very accurately the exact level at which the lowermost brick course Q is to be placed, and this 55 having been ascertained, the angle iron is rested in the lower elbow of the hanger K and by manipulation of the screw H, the latter is raised or lowered until the top surface 60 of the horizontal flange N of the angle iron is at the exact level desired. This involves not only the hand-actuated movement upward and downward within the box of the top flange K' of the hanger K, but as well, 65 the movement accordingly of the clip J and

the clamping of its bolt or screw L against the vertical web M of the angle iron. Since these constructions are placed at desired intervals in general horizontal alignment, this will result in the angle iron being accurately 70 and firmly held throughout its length at just the elevation desired, and laying of the brick courses may proceed accordingly. Generally it is preferable that the inner edges of the brick thus employed shall be spaced from the hardened concrete surface to permit the slushing-in of mortar or other holding element. As to the space P shown in Figure 75 6 as separating the flange M of the angle iron from the line of the inner face of the depending clip end J' this is relatively thin, but since in some cases the wooden forms when filled in with concrete may bulge outwardly somewhat in places, it may at times be desirable to move one or more of the angle 80 iron supports outwardly somewhat to compensate for this and keep the angle iron as finally positioned in true alignment. To effect this, it may be necessary to move the angle iron outwardly somewhat relatively 85 to the bracket K, and this may be easily done when needed by retracting the holding bolt L slightly accordingly and placing between the vertical web M of the angle iron and the central portion of the holder K a shim or 90 filler of desired thickness, such as I have indicated at O in Figure 6. By contrast, however, the indicated inner line of the courses 95 of brick being substantially coincident with the outer face of the wooden form F, whose further utility has been terminated by the hardening of the concrete, a much wider space for the slushed-in mortar would be 100 available, and the greatest space of all, affording as well an interlock for the mortar 105 when hardened, due to the presence therein of the bolt H, is afforded by the box-surrounded space E.

In the slightly variant forms of box or shell structure illustrated in horizontal section in Figures 7 and 8 respectively, the 110 slideable up and down movement of the hanger and the clip relatively to the box and their actuation accordingly by the screw H, is substantially the same, but in the form 115 shown in Figure 7 the guiding rib R on either side of the box structure and the cutting away accordingly of the hanger and clip indicated at S, is positioned slightly within the outer or exposed face of the box 120 structure, whereas in Figure 8 the flanges T of the box structure, and cut-away portion V of these movable elements are positioned at the outer edge or face of the box. In either form, however, the functioning of 125 these parts relatively to the angle iron M upon which the brick courses Q are supported, is the same.

What I claim is:

1. Means for affording an adjustable 130

structural support for an angle iron upon which finishing courses of brick are designed to be rested along the face of a previously erected structure, comprising a shell adapted to be fixed in position relatively to said previously erected structure during its construction, an adjusting screw rotatably positioned within said shell, and a plurality of angled members operatively connected with said adjusting screw and adapted to cooperatively engage the vertical web portion of an angle bar, the horizontally extending web of which is supported from beneath by a laterally projecting portion of one of said angled members.

2. In combination with a supporting structural body, shell members each of which has an outwardly facing open side alignedly integrated therewith at selected intervals thereon, a screw member rotatably supported in each of said shell members and externally accessible through the open side thereof, a pair of angled supporting members appurtenant each of said shell members and its corresponding screw member, one web of each of said angled supporting members being operatively engaged by their corresponding screw member for effecting the raising or lowering thereof, and said supporting members being adapted to operatively engage the opposite faces of one web of an interposed angle iron, the other web of which latter is adapted to be supported from beneath by a laterally projecting portion of one of said angled supporting members.

3. The combination, with an open-sided shell member, of a screw member rotatably supported therewithin, and a pair of cooperating angled supporting members each operatively connected with said screw member for effecting their raising and lowering relatively to said shell member, said angled supporting members being adapted to operatively and supportingly engage and carry with them an angle iron whose adjusted positioning relatively to said shell member is desired.

4. In combination with a shell member adapted for association with a cementitious structural mass, a screw member rotatably supported within said shell member, a pair of partially projecting members each operatively connected with said screw member and adapted to be moved upwardly or downwardly relatively to said shell member by the actuated movement of said screw members, said partially projecting members being adapted to cooperatively engage an interposed angle bar and to effect the regulated positioning thereof relatively to said shell member according to their screw-actuated movement.

5. The combination, with a supporting structure, of a plurality of shell members

located at selected intervals thereon in general and approximate alignment, a screw member rotatably supported by each of said shell members, a pair of member appurtenant each of said shell members and operatively connected with the corresponding screw member, adapted to cooperatively engage that portion of an interposed angle iron located opposite their corresponding shell member, and means appurtenant each of said shell members and their associated parts whereby irregularities in its aligned positioning may be compensated for as regards the seizure and support of the adjacent portion of an angle iron by said cooperative members.

6. An adjustable angle-iron support adapted for integrated structural association with a supporting body, comprising, in combination, a supporting shell member, a pair of angle-iron-engaging members slidably positioned partly within said shell and operatively held thereby within a limited path of possible travel, and a rotatable screw member positioned within said shell and operatively connected with said angle-iron-engaging members, whereby the latter may be regulatedly moved upwardly or downwardly with respect to the shell.

7. In combination with a pair of angled members between which an angle iron is adapted to be positioned, a supporting shell structure relatively to which said angled members are limitedly movable, said shell structure being adapted to be positioned in an exposed surface portion of an erected structure, and a screw member rotatably supported by said shell and operatively connected with said angled members, whereby the latter and their supported angle iron section may be regulatedly moved upwardly or downwardly relatively to said shell structure.

In testimony whereof I sign this specification.
